(57) **CLAIM**

The ornamental design for an external lock cover, substantially as shown and described.

DESCRIPTION

FIG. 1 is an isometric view of a preferred embodiment of the design of my invention, showing the cover mounted on a truck door;

FIG. 2 is a rear view of the preferred embodiment of the invention; and,

FIG. 3 is a side view of the preferred embodiment of the invention.

The portion of the trunk door illustrated in the drawings in dot and dash does not constitute a part of the invention.

1 Claim, 2 Drawing Sheets

FIG. 1

FIG. 2

FIG. 3
